Chambersburg, Pa., a corporation of Pennsylvania

Application October 16, 1950, Serial No. 190,421

15 Claims. (Cl. 60—97)

1

This invention relates to control of impact forging apparatus wherein a work piece is forged by means of one or more rapidly moving rams.

The principal object of the invention is to provide an apparatus which will produce an indicating and controlling signal from the virtually instantaneous position of a rapidly moving ram.

The invention is well adapted for use in a forging apparatus of the type wherein two horizontally aligned rams, operated by pressurized fluid, serve to forge by impact work pieces successively interposed between them.

Another object of the invention, therefore, is to provide an indicating and controlling arrangement for use in a forging apparatus of that type. Accordingly, the invention will be described with reference to its application to such apparatus.

In such a forging apparatus, it is desirable to have provision for differentially controlling the supply of pressurized fluid to the rams to establish the exact plane of impact of the rams. In my prior Patent No. 2,615,306, issued Oct. 28, 1952, there is disclosed and claimed an apparatus of this type in which differential control of the supply of pressurized fluid to the rams is provided through the medium of a common controlling valve actuated by a motor which may be part of a Selsyn system to enable remote control. By the present invention, there is provided an indicating and controlling arrangement which includes means for sensing excess travel of either ram, and in which the indicating and controlling functions are instituted by such means.

Reference is now made to the accompanying drawings in which the present invention is shown applied to a forging apparatus of the character disclosed in the above-mentioned application.

In the drawings:

Fig. 1 is a view, partly in longitudinal section and partly in elevation, of the forging apparatus embodying the invention;

Fig. 2 is a schematic illustration of the controlling arrangement employed in conjunction with the impacter rams;

Fig. 3 is a diagrammatic illustration of the electrical system for controlling the operation of the apparatus;

Fig. 4 is a diagrammatic illustration of the preferred form of the indicating and controlling circuit provided according to this invention; and

Fig. 5 shows the voltage pulse which is produced whenever one of the sensing devices is activated.

Referring first to Fig. 1, there are shown two horizontally aligned rams 10 and 10a which are

2

movable within fluid cylinders 11 and 11a, the rams moving toward and away from each other during a complete cycle of operation. Removably attached to the rams are dies 12 and 12a which engage a work piece (not shown) to forge the same. The dot and dash illustration shows the rams and the dies in the forward positions.

The rams are activated during the work stroke by pressurized fluid supplied to the cylinders from 10 a common fluid line 13 through intake conduits 14 and 14a. Preferably, the rams are activated by means of compressed air, the line 13 being connected to a suitable source of compressed air. The air is supplied to the cylinders through valve devices 15 and 15a.

The ram-containing cylinders are shown mounted on a supporting framework 17 which may also serve to support certain controlling valves as hereinafter described. The supply conduit 13 extends longitudinally through the supporting framework, as does also a common exhaust conduit (not visible) through which the air is exhausted from the cylinders during the return stroke.

25 Referring now to Fig. 2, illustrated therein are the controlling valves associated with the ram 10 and its cylinder 11, it being understood that similar valves are provided in association with the ram 10a and its cylinder 11a. A fluid operable valve 18 controls the air input from conduit 14 to ports 19 (one visible) which extend to the interior of the cylinder at the pressure end thereof. A second fluid-operable valve 20 controls the air exhaust to conduit 21 which extends to the 30 exhaust line. In the illustration, the valve 18 is closed and the valve 20 is open, this being the condition for exhaust. When the valve 20 is closed and the valve 18 is open, air is admitted to the cylinder from conduit 14.

35 It should be noted that the ports 19 are spaced from the driving end of cylinder 11, and a bypass port 22 is disposed at the end of the cylinder and is arranged to by-pass the ports 19 through a spring-biased check valve 23 whose spring tends 40 to maintain it closed. The purpose of this will be explained presently.

45 Referring still to Fig. 2, the inlet valve 18 for the ram 10 and its associated cylinder 11 is controlled by pressurized fluid, preferably 50 compressed air, through a conduit 24 extending to easing 25 of a differential controlling valve 26. In like manner, the input valve for the other ram and its associated cylinder is controlled through the fluid conduit 27 which extends 55 from said input valve to the other side

of said controlling valve 26. The conduits 24 and 27 communicate through valve casing 25, with a common fluid conduit 28 which extends from the valve casing 25 to the casing 29 of a solenoid operated valve 30. The purpose of the differential controlling valve 26 is to control differentially the supply of fluid to the input valves for the two rams, thereby to control the relative timing of the operation of the input valves and thus establish the exact plane of impact of the rams. The valve 26 is shown connected through a crank arm 31, link 32 and crank arm 33 to reducing gears 34 and 35, the latter gear being on the shaft 36 of a reversible driving motor 37. As hereinafter described, the motor 37 is controlled by position-sensing devices associated respectively with the two rams.

The exhaust valve 20 for the ram 10 and its associated cylinder 11 is controlled through branch 38 of a T conduit 39, the other branch 40 of which extends to the exhaust valve for the other ram and its associated cylinder. The leg of conduit 39 extends to the casing 29 of the valve 30.

The valve 30 is spring biased to the position shown by means of spring 41, and it is actuated against the action of the spring by a solenoid 42. The casing of this valve has spaced annular recesses 43 and 44 to which are respectively connected the conduits 28 and 39. Between these annular recesses is a third annular recess 45 to which a compressed air supply conduit 46 extends. The conduit 46 is connected to the main air supply line 13 hereinbefore mentioned. Exhaust conduits 47 and 48 extend into the ends of valve casing 29, and these conduits are connected to the main exhaust line. The valve member 30 has spaced portions 49 and 50 which control the valve ports.

When the solenoid 42 is deenergized as shown, the input valve 18 is in communication with the air supply conduit 46 and the valve is held closed. At the same time, the exhaust valve 20 is in communication with exhaust conduit 48 and the valve is open. When the solenoid 42 is energized, the valve member 30 moves to the right, and the exhaust valve 20 is placed in communication with the air supply conduit 46 and is cut off from the exhaust conduits. At the same time the input valve 18 is cut off from the air supply conduit 46 and is placed in communication with the exhaust conduit 47. At such time, therefore, the exhaust valve 20 is closed and the input valve 18 is opened.

After the impacting stroke of ram 10, the ram is returned by air pressure supplied to the cylinder 11 through branch 51 of a T conduit 52 whose other branch arm 53 extends to the cylinder of the other ram. The leg of the T conduit 52 extends to the casing 54 of a valve 55 which is biased by spring 56 and is operable by the solenoid 57. An air supply conduit 58 and an exhaust conduit 59 also extend to the valve casing 54. These conduits are connected respectively to the main air and exhaust lines hereinbefore mentioned. Normally, the valve 55 is in the position shown, and the conduit 52 is in communication with the exhaust conduit 59. However, when solenoid 57 is energized, the conduit 52 is placed in communication with the air conduit 58 and is cut off from the exhaust conduit 59. At such time, air is supplied to the cylinder 11 to move the ram back to its initial position.

The purpose of the check valve 23 may now

be understood. During the return of the ram 10, the head thereof closes the ports 19 and air is trapped at the end of the cylinder, providing an air cushion which prevents the ram from striking the end of the cylinder. With the ram stopped in the position shown in Fig. 2, the cylinder is closed against input of air through the ports 19. However, the check valve 23 and the by-pass 22 permits air to enter the cylinder in sufficient amount to move the ram until the ports 19 are cleared.

Referring now to Fig. 3, an A. C. supply line 60, 61, e. g. a sixty cycle supply line, serves as a common source of electrical supply for the various elements shown through the manual switch 62. The energization of solenoid 42 is effected by means of a timer 63 under control of a motor driven switch mechanism 64. The energization of solenoid 57 is effected by the switch mechanism 64 alone.

The electrical control system is conditioned for operation, after closure of switch 62, by a contactor 65 which is under control of start and stop switches 66 and 67. The contactor 65 comprises a solenoid 68, an armature 69, and a biasing spring 70 which tends to maintain the armature in the position shown. When the start switch 66 is momentarily closed, the solenoid 68 is energized through a circuit which includes conductor 71, conductor 72, and conductor 73. The contactor 65 locks itself in through contacts 74 which close a branch circuit in shunt with the start switch 66 and including conductors 75 and 76.

Energization of the contactor closes an energizing circuit for the motor 77 of the device 64 through closure of contacts 78 and 79. This circuit includes conductors 80, 81, 82 and 83. The motor 77 drives, through reduction gearing 84, a shaft 85 on which are mounted cams 86 and 87. These cams actuate switches 88 and 89 respectively in sequential and timed relation. These switches control energization of the solenoids 42 and 57 as hereinafter described. Also mounted on shaft 85 is a cam 90 which actuates switch 91. This switch serves to control the indicating and controlling circuit hereinbefore described. The movable arms of the above-mentioned switches are biased toward the cams, as by means of springs (not shown).

The timer 63 may be of the character disclosed in my above-mentioned application. Since the present invention is not concerned with the timer per se, there is no need here for illustration or description of the timer construction. The operation of the timer is initiated through a circuit 92 connected to terminals 93 of the timer. The initiating circuit 92 extends by way of conductor 94 through contacts 95 of contactor 65, through conductor 96 to switch 98, and back to the timer by way of conductor 97. Thus, it will be seen that the switch 98 is included in the initiating circuit and controls the same.

The timer has energy input terminals 99 which are connected to the supply line 60, 61 by way of conductors 99. A lamp 100 is connected across the latter conductors to indicate closure of switch 62. A second lamp 101 is connected to terminals 102 of the timer and indicates when the timer is conditioned for operation. Start and stop switches 103 and 104 are connected to terminals 105, 106 and 107 of the timer and serve to control the conditioning thereof.

The impact-controlling solenoid 42 is connected between terminal 108 on the timer and

one of the supply line conductors through connections 109 and 110.

Considering the operation of the apparatus as thus far described, the operator first closes the line switch 62 and then presses the push button start switch 66, whereupon the contactor 65 is energized and locks itself in. The contactor remains energized until such time as the operator presses the push button stop switch 67 which is connected in the holding circuit of the contactor. The energization of the contactor starts the motor 77 which runs continuously until the contactor is deenergized. Consequently, the switches 88 and 89 are cyclically operated by their motor driven cams 86 and 87. The operating sequence provided by the design of the cams is such that switch 88 first conditions the timer 63 for operation and the solenoid 42 is energized by the timer to cause operation of the rams through their power stroke, and the switch 89 closes after switch 88 opens to energize solenoid 57 which causes return of the rams.

As previously mentioned, the purpose of valve 26 (Fig. 2) is to control differentially the supply of fluid to the input valves for the two rams, thereby to control the relative timing of the operation of the input valves and thus establish the exact plane of impact of the rams. In accordance with the present invention, the valve 26 is automatically controlled by position-sensing devices 111 and 112 (see Fig. 1) associated respectively with the two rams, the said devices serving to control the operation of the actuating motor 37 for valve 26 through the medium of the controlling circuit shown in Fig. 4.

Referring to Fig. 1, the position-sensing devices 111 and 112 are shown mounted on a common supporting bracket 113 which spans the space between the ram cylinders 11 and 11a, and the ends of which are secured to said cylinders. As may be seen from the cross-sectional illustration of the device 111, each of the sensing devices may comprise a permanent magnet core 114 and a surrounding coil 115, both enclosed in a magnetic casing or housing 116 except for a small clearance around the extended end of magnet 114. The two sensing devices are exactly located so that the lower end of each core magnet is slightly above the path of travel of the associated ram and is so positioned that the magnetic field of the core magnet will be substantially affected only if the associated ram exceeds its intended extent of travel. In other words, if the plane of impact of the two rams is exactly centered, neither of the sensing devices 111 and 112 will be affected sufficiently to cause any corrective action. However, if the plane of impact shifts due to unbalanced operation of the rams, one of the rams will over-travel and will activate the associated sensing device to cause a corrective action as hereinafter described. The activation of either sensing device is produced by a substantial change in the distribution of the magnetic lines of force of its core magnet due to sufficient entry of the ram into the magnetic field to produce such change. This action causes a voltage surge in the coil of the sensing device, which surge is in the form of a pulse as represented at 117 in Fig. 5.

Referring now to Fig. 4, there is shown a circuit arrangement by which the sensing devices 111 and 112 are caused to control the operation of the actuating motor 37 for the valve 26. Power supply conductors 118, which may be connected to the same source as the supply conductors of Fig. 3, extend through a manual on-off switch

119 to a conventional rectifier unit 120 which provides D. C. operating voltages for two thyatrons 121 and 122. The rectifier unit 120 requires no detailed description and it suffices to note that the operating voltages for the thyatrons are derived from series-connected resistors 123 and 124, the latter extending to ground. The anodes of the thyatrons are connected through indicator lamps 125 and 126, and through the cam-operated switch 91, to a tap on resistor 123. As previously described and as shown in Fig. 3, the switch 91 is cyclically operated by virtue of the fact that it is part of the motor driven switch mechanism 64. The cathodes of the thyatrons 121 and 122 are connected to a tap on resistor 124. It will be seen that when the switch 91 is closed, the anodes of the thyatrons are at a predetermined positive D. C. voltage relative to the cathodes.

The control grid circuit of thyatron 121 extends through a resistor 127 and the coil of sensing device 111 in series to ground, a by-pass condenser 128 being connected as shown. Similarly, the control grid circuit of thyatron 122 includes resistor 129, the coil of sensing device 112, and a by-pass condenser 130. Normally, the control grids of the thyatrons are sufficiently negative relative to the cathodes to prevent operation of the thyatrons, but when a voltage surge is produced in either of the sensing devices 111 and 112, the grid of the associated thyatron is driven in the positive direction sufficiently to fire that thyatron, assuming of course that the switch 91 is closed.

The operating motor 37 for valve 26 is energized through branch supply conductors 131 under control of relays 132 and 133 whose windings 134 and 135 are included respectively in the anode circuits of thyatrons 121 and 122 in shunt with the indicating lamps 125 and 126. The motor 37 is a conventional reversible single phase motor having a start winding 136 and a run winding 137. These windings are connected as shown to the contacts of the two relays and to the supply connections 131. Normally, the two relays are de-energized and their contacts are open. When relay 134 is energized, closure of its contacts causes the motor 37 to run in the forward direction, while when relay 135 is energized closure of its contacts causes the motor 37 to run in the opposite direction. It will be understood, of course, that only one of the relays is energized at a time.

The operation of the controlling and indicating circuit of Fig. 4 as a part of the over-all operation may now be understood. The manual switch 119 is closed at the same time that the manual switch 62 of Fig. 3 is closed. A pilot lamp 138 indicates closure of the switch 119. During the operation of the impacter rams as previously described, the cam-operated switch 91 is cyclically operated, the design or shape of its operating cam 90 being such that the switch is closed at the same time that the switch 88 is closed. It will be recalled that the switch 88 controls the forward movement of the rams, as previously described. Thus, it will be seen that the switch 91 is closed to condition the thyatrons 121 and 122 for possible operation during the forward movement of the rams. Subsequent opening of the switch, of course, renders the thyatrons inoperative, and if either of the thyatrons has been fired, stops the operation thereof.

As previously mentioned, neither of the thyatrons will operate unless its control grid receives an actuating pulse from the associated sensing

device 111 or 112. If the operating rams are balanced during a particular operation neither of the sensing devices 111 and 112 will be activated. Suppose, however, that the ram 19 (Fig. 1) should over-travel during a particular operation. This will cause activation of the sensing device 114 and consequent firing of the thyratron 124 which, in turn, will light the indicator lamp 125 and will energize relay 134. The latter will cause the motor 37 to run in a forward direction to shift the valve 26 so as to make the desired corrective adjustment. Likewise, if the ram 18a were to over-travel, the thyratron 122 would be fired with consequent energization of lamp 126 and relay 135, the latter causing operation of motor 37 in the reverse direction to make the desired corrective adjustment. In actual practice, the closure time of switch 91 is quite short and in case of unbalance of the rams only slight adjustment is made at each stroke, thus preventing hunting action.

It will be apparent from the foregoing description that the arrangement shown in Fig. 4 serves both to give an indication of unbalance of the rams (through the medium of lamps 125 and 126) and to effect an automatic corrective action. However, the invention contemplates an arrangement in which either or both of these functions are performed. For example, the automatic corrective action could be eliminated by providing for manual control of the motor 37 by an operator who would be apprised by the lamps 125 and 126 of the necessity for corrective adjustment. However, it will usually be desired to provide for such rapid operation of the rams as to make manual corrective adjustment very difficult. Therefore, it is preferred to provide for automatic corrective adjustment as shown in Fig. 4 and as described above.

While a particular application and a preferred embodiment of the invention have been illustrated and described, it will be understood that the invention is not limited thereto. In its broadest aspect, the invention contemplates the provision of position-sensing means in cooperative association with an impacting member of a forging apparatus, and the provision of means for effecting indication and/or automatic control action in response to activation of such sensing means.

I claim:

1. In an apparatus of the class described, a pair of opposed fluid-operated pistons, a common source of operating fluid for said pistons, a pair of fluid-operated valves for controlling the supply of operating fluid to said pistons, common valve means for differentially controlling the supply of fluid to said valves, means responsive to excessive travel of either piston, and means operable by said last means for actuating said common valve means so as to equalize the movements of the pistons.

2. In an apparatus of the class described, a pair of opposed fluid-operated pistons, a common source of operating fluid for said pistons, a pair of fluid-operated valves for controlling the supply of operating fluid to said pistons, common valve means for differentially controlling the supply of fluid to said valves, a pair of sensing devices associated respectively with said pistons and responsive to excessive travel thereof, and means operable by said devices for directionally actuating said common valve means according to the sensing device activated in any instance so as to equalize the movements of the pistons.

3. In an apparatus of the class described, a pair of opposed fluid-operated pistons, a common

source of operating fluid for said pistons, a pair of fluid-operated valves for controlling the supply of operating fluid to said pistons, common valve means for differentially controlling the supply of fluid to said valves, a pair of electromagnetic sensing devices associated respectively with said pistons and responsive to excessive travel thereof, a pair of relays, means operable by said sensing devices for selectively energizing said relays according to the sensing device activated in any instance, and means controlled by said relays for directionally actuating said valve means so as to equalize the movements of the pistons.

4. In an apparatus of the class described, a pair of opposed fluid-operated pistons, a common source of operating fluid for said pistons, a pair of fluid-operated valves for controlling the supply of operating fluid to said pistons, common valve means for differentially controlling the supply of fluid to said valves, a reversible electric motor connected to said valve means to actuate the latter in either direction, a pair of relays arranged to effect operation of said motor in either direction, a pair of sensing devices associated respectively with said pistons and responsive to excessive travel thereof, and means operable by said devices for selectively energizing said relays, whereby to actuate said valve means so as to equalize the movements of said pistons.

5. In an apparatus of the class described, a pair of opposed fluid-operated pistons, a common source of operating fluid for said pistons, a pair of fluid-operated valves for controlling the supply of operating fluid to said pistons, common valve means for differentially controlling the supply of fluid to said valves, a reversible electric motor connected to said valve means to actuate the latter in either direction, a pair of relays arranged to effect operation of said motor in either direction, a pair of electromagnetic sensing devices associated respectively with said pistons and responsive to excessive travel thereof, and a pair of thyratrons operable respectively by said devices for selectively energizing said relays, whereby to actuate said valve means so as to equalize the movements of said pistons.

6. In an apparatus of the class described, a pair of opposed fluid-operated pistons, means for effecting cyclic operation of said pistons, valve means arranged to control differentially the operation of said pistons, a reversible electric motor connected to said valve means to actuate the latter in either direction, a pair of relays arranged to effect operation of said motor in either direction, a pair of sensing devices associated respectively with said pistons and responsive to excessive travel thereof, and means operable by said devices for selectively energizing said relays, whereby to actuate said valve means so as to equalize the movements of said pistons.

7. In an apparatus of the class described, a pair of opposed fluid-operated pistons, means for effecting cyclic operation of said pistons, valve means arranged to control differentially the operation of said pistons, a reversible electric motor connected to said valve means to actuate the latter in either direction, a pair of relays arranged to effect operation of said motor in either direction, a pair of sensing devices associated respectively with said pistons and responsive to excessive travel thereof, and a pair of thyratrons operable respectively by said devices for selectively energizing said relays, whereby to actuate said

valve means so as to equalize the movements of said pistons.

8. In an apparatus of the class described, a reciprocally movable member, cyclically-operable switch means, a motor for driving said switch means, means controlled by said switch means for cyclically operating said member, stationary sensing means adjacent to the path of travel of said member and responsive to the presence thereof, normally-inoperative means controllable by said sensing means to govern the operation of said member, and switch means driven by said motor for rendering the last-recited means operable only during movement of said member in a direction to approach said sensing means.

9. In an apparatus of the class described, a reciprocally movable member, cyclically-operable switch means, a motor for driving said switch means, means controlled by said switch means for cyclically operating said member, stationary sensing means adjacent to the path of travel of said member and responsive to the presence thereof, a thyatron operable by said sensing means, means controllable by said thyatron to govern the operation of said member, and switch means driven by said motor for rendering said thyatron operable only during movement of said member in a direction to approach said sensing means.

10. In an apparatus of the class described, a fluid-operated reciprocally movable piston member, cyclically-operable switch means, a motor for driving said switch means, means controlled by said switch means for cyclically operating said member, stationary sensing means adjacent to the path of travel of said member and responsive to the presence thereof, valve means for governing the operation of said member, normally-inoperative means controllable by said sensing means to actuate said valve means, and switch means driven by said motor for rendering the last-recited means operable only during movement of said member in a direction to approach said sensing means.

11. In an apparatus of the class described, a pair of opposed reciprocally movable members, cyclically-operable switch means, a motor for driving said switch means, means controlled by said switch means for cyclically operating said members, a pair of sensing devices associated respectively with said members and responsive to excessive travel thereof, means for differentially controlling the movement of said members, normally-operative means controllable by said sensing devices to actuate said controlling means, and switch means driven by said motor for rendering said last-recited means operable only during movement of said members toward said sensing devices.

12. In an apparatus of the class described, a pair of opposed fluid-operated piston members, cyclically-operable switch means, a motor for driving said switch means, means controlled by said switch means for cyclically operating said members, a pair of sensing devices associated respectively with said members and responsive to excessive travel thereof, common valve means for differentially controlling the movement of said members, normally-inoperative means controllable by said sensing devices to actuate said valve means, and switch means driven by said motor for rendering said last-recited means operable only during movement of said members toward said sensing devices.

13. In an apparatus of the class described, a

pair of opposed fluid-operated piston members, cyclically-operable switch means, a motor for driving said switch means, means controlled by said switch means for cyclically operating said members, a pair of sensing devices associated respectively with said members and responsive to excessive travel thereof, common valve means for differentially controlling the movement of said members, means including a pair of thyatrons controllable by said sensing devices to actuate said valve means, and switch means driven by said motor for rendering said thyatrons operable only during movement of said members toward said sensing devices.

15. 14. In combination, fluid pressure-actuated means including a member operable through a work stroke and a return stroke, means including a first solenoid-operated valve for supplying pressurized fluid to said first-mentioned means so as to operate said member through the work stroke, means including a second solenoid-operated valve for supplying pressurized fluid to said first-mentioned means so as to operate said member through the return stroke, cyclically-operable switch means, a motor for driving said switch means, means controlled by said switch means for successively energizing the operating solenoids of said valves to cyclically operate said member, a third valve arranged to control the amount of pressurized fluid supplied to said member to operate it through the work stroke, stationary sensing means adjacent to the path of travel of said member and responsive to the presence thereof, normally-inoperative means controllable by said sensing means to actuate said third valve, and switch means driven by said motor for rendering the last-recited means operable only during movement of said member through the work stroke.

15. In combination, a pair of opposed fluid-operated piston members, means including a first solenoid-operated valve for supplying pressurized fluid to said members so as to drive them toward each other, means including a second solenoid-operated valve for supplying pressurized fluid to said members so as to return them, cyclically-operable switch means, a motor for driving said switch means, means controlled by said switch means for successively energizing the operating solenoids of said valves to cyclically operate said members, a third valve arranged to control differentially the amounts of pressurized fluid supplied to said members to operate them toward each other, sensing means responsive to excessive travel of either of said members, normally-inoperative means controllable by said sensing means to actuate said third valve so as to equalize the movements of said members, and switch means driven by said motor for rendering the last-recited means operable only during movement of said members toward each other.
